UNITED STATES PATENT OFFICE.

WILLIAM L. CHURCHILL, OF CHICAGO, ILLINOIS, ASSIGNOR TO NATIONAL PNEUMATIC SERVICE COMPANY, OF CHICAGO, ILLINOIS, A CORPORATION OF ILLINOIS.

STATION FOR STORE-SERVICE APPARATUS.

SPECIFICATION forming part of Letters Patent No. 726,815, dated April 28, 1903.

Application filed July 3, 1902. Serial No. 114,196. (No model.)

To all whom it may concern:

Be it known that I, WILLIAM L. CHURCHILL, a citizen of the United States of America, residing at Chicago, in the county of Cook and 5 State of Illinois, have invented certain new and useful Improvements in Stations for Store-Service Apparatus, of which the following is a specification.

My invention relates to certain new and 10 useful improvements in stations for store-service apparatus; and its object is to provide a station for use in connection with an entire system of store-service apparatus which I have invented, the general features of which 15 are shown in application filed March 26, 1902, and allotted serial number 100,029. The cash-carriers in use with this system of apparatus may be those shown in either of my applications on cash-carriers filed March 26, 1902, 20 and allotted serial numbers 100,026, 100,027, and 100,028. The station described in this specification is that commonly called the "middle" station as distinguished from the cashier's station and the end station or station 25 farthest removed from the cashier's station.

My invention consists in certain novel features of construction, which are clearly shown in the accompanying drawings and described in this specification.

30 In the drawings, Figure 1 is a side elevation of the entire station. Fig. 2 is a section in the line 2 2 of Fig. 1. Fig. 3 is a perspective of one end of the terminal track and its supporting-bracket. Figs. 4 and 5 are sections in the line 4 4 of Figs. 6 and 7, Fig. 4 showing the switching mechanism in its normal position and Fig. 5 showing it in position to deflect a cash-carrier from the main receiving-track to the terminal track. Fig. 40 6 is a top plan of the parts above the line 6 6 of Fig. 4. Fig. 7 is a plan of the parts below said line, showing the vertical member of the brackets in horizontal section. Fig. 8 is a plan of the junction of the switch and the 45 main receiving-track when the switch is in the position shown in Fig. 5. Fig. 9 is a side elevation of the same, showing the bracket in section, the line of section being indicated at 9 9 of Fig. 8. Fig. 10 is a section in the 50 line 10 10 of Fig. 9. Fig. 11 is a section in

the line 11 11 of Fig. 4 looking in the direction of the arrow, and Fig. 12 is a plan of the junction of the switch with the terminal track when the switch is in the position shown in Fig. 4.

55 Referring to the drawings, A is the main receiving-track, having below it a cable B, moving in the direction of the arrow. A' is the sending-track. It is provided with a cable B', moving in the opposite direction from the cable B. The track A' is offset or staggered with relation to the track A, and both are supported from the inside in order to accommodate cash-carriers having downwardly-projecting hooks upon their sides, which embrace and extend inwardly underneath the rails of the tracks. Above the track A at points where stations are located is a terminal track C, supported upon a bracket D. The track C swings in a loop from the bracket 70 D downward and slightly to one side and again through the bracket D, where it is immediately under the track A', and after continuing in this direction for some slight distance the rails end, permitting the carrier 75 to be removed from them. The curves of the track C are clearly shown in Figs. 1 and 2. It is not material whether the track C runs in this particular manner, but may be led away from the main track in any other 80 suitable manner to bring the terminal track within easy reach of the salesman. A bracket E supports upon a horizontal pivot or shaft e two arms e', which bear upon their end a switch-track F. A pair of springs e², Fig. 11, 85 bear upon the arms e' and tend to force the track F to the position shown in Fig. 5. When the arms e' and the track F are in their normal position—that is, the position shown in Fig. 4—the rear ends of the switch-track F 90 meet the ends of the terminal track C just at the bracket D, and the front ends are raised sufficiently to permit the free passage of carriers beneath it. The rails of the switch-track F are preferably made of flat material, 95 as is clearly shown in the drawings. The bracket D has at the point of attachment of the rails of the track C two sockets d to receive the ends of the switch-track F, thereby making a tight connection between said 100

switch-track F and the terminal track C. The receiving-track A has a small gap a , and when the switch-track F is swung downward—that is, when it is in the position 5 shown in Fig. 5—the end of the switch-track F covers this gap and comes in contact with one end of the track A. At the point where the switch-rails F strike the track A are posts or rests h^3 , which also form stops for the 10 switch-track in its deflected position. The ends of the rails of the switch-track F are cut away, as shown in Fig. 8, to permit a tight joint. The gap in the rails of the track A is bridged by two small yoke-shaped rails 15 a' , which extend around the gap on the inside. Inasmuch as the box of the cash-carrier merely slides upon the rails with its bottom in contact therewith, it is immaterial whether the rails are placed near together or 20 far apart—that is, within the limits of the hooks of the cash-carriers. The result of this is that when the switch-track F is in its upper position and it is desired that the cash-carrier pass over the gap A instead of being 25 deflected it will merely slide by the gap on these yoke-shaped rails a' . When, however, the track F is down—that is, in the position shown in Fig. 5—the cash-carriers will be deflected by this track and pass up upon the 30 switch-track, the hooks, which project downward from the side thereof, passing through the gap a and permitting the carrier to rise on the switch-track without any difficulty. Assuming now that the switch is in the position 35 shown in Fig. 5 and a carrier comes to it, it will rise, as previously mentioned, upon the switch-track F, drawing the cable B with it. The cable will of course exert a considerable downward tension upon the carrier, 40 and consequently upon the switch-track. When the carrier passes the supporting-arms e , the weight of the carrier and the pull of the cable will instantly draw the switch to the position shown in Fig. 4, bringing the 45 opposite end of the track F into the sockets d of the terminal track and permitting the carrier to run off upon this terminal track. The tilting of the switch-track F from the position shown in Fig. 5 to that shown in 50 Fig. 4 is furthered by a pair of guide-rails G, Figs. 4, 5, and 6, which would instantly force the track to the desired position independently of the pull of the cable. The rails G have another function, which will now be described. It will be noted in Fig. 6 that these 55 guide rails or tracks converge at g , forming a cam-surface. This cam-surface is so arranged that it presses upon the latch of the cable-gripping mechanism of the cash-carrier and releases this mechanism from the cable, thereby permitting the cable to fall back to its normal position. When the cable is released, the carrier runs on of its own momentum along the track C, swings around in 60 the loop of said track, and stops somewhere between said loop and the end of the track C. This is the operation of the switching mechan- 65

ism. It remains now only to describe the means by which the switch-track F is moved into the position shown in Fig. 5 from its normal position. (Shown in Fig. 4.) This is accomplished automatically by the carriers themselves. It is obvious that in systems of this class where carriers intended for several different stations are run upon one track some automatic selecting system must be used. The device on the carrier by which this is accomplished consists in a pair of projecting lugs on each box, these lugs being arranged at different heights, depending upon the station 75 to which they are intended to run. The term "lugs" is used very broadly in this connection, several variations in the form of the projecting members being used, lugs, washers, and rollers having all been used. 85

The station-selecting apparatus will now be described. A bracket H is supported by the track A at the gap a , and this bracket supports a pair of levers H' by means of pivotal pins h , said levers having cam-surfaces h' 90 upon their lower sides. These cam-surfaces are adapted to engage the projecting lugs o upon the carriers, one of which is shown at O. The levers H' are connected by links i to two bell-crank levers I, pivotally supported upon 95 a bracket I', which is connected to and supported by the track A. The links i are provided with a number of holes i' , which permit the levers H' to be adjustable with respect to the bell-crank levers in order to make the 100 height of the levers correspond with the height of the projecting lugs upon the carriers. It is obvious that if a carrier having lugs low down upon it passes along the track A the levers H' will not be affected by the cams 105 unless they are connected with the lower ends of the links i . It will be seen then that all that it is necessary to do in order to make the levers H' selectively operative is to make their height from the track slightly less than 110 the height of the lugs upon the carrier. Assuming now that the carrier reaches the levers and has lugs at the proper height to operate them, the levers will be raised, push upon the links, and rotate the bell-crank levers I, so as to move their lower ends to the left. To the arms e , which support the switch-track F, is rigidly connected an arm e^3 by means of the shaft c , and from the extremity of this arm extends a link J. A similar link 115 J' extends from the bracket E to the extremity of the link J. These two links form a toggle-lever which when operated can move the extremity of the arm e^3 , and thereby rotate the arms e and the switch-track F. The 120 pivot of the toggle-lever is connected to a block j , and the lower ends of the two bell-crank levers I are connected by a rod i^2 , upon which is a block i^3 . The block j and the block i^3 are connected by a suitable coupling- 125 rod K. The operation of the entire device will now 130 be apparent. When the levers H' are raised, as heretofore explained, the bell-crank lever

is rotated from the position shown in Fig. 4 to that shown in Fig. 5 and the coupling-rod K is drawn to the left, thereby drawing the toggle-lever from the position shown in Fig.

5 to that shown in Fig. 5, thus pulling down the arm e^3 and rotating the arms e' and the track F to the position shown in Fig. 5. The carrier then runs up upon the track F, and when it passes the center of this track the

track swings back into the position shown in Fig. 4, as heretofore explained. The center of the toggle-lever, formed of the links J J', swings past a line extending through the pivot-point of these links and locks the track

15 firmly in place. The guide-rails G then release the cable, permitting the carrier to run on the terminal track C, as heretofore explained. A spring k, Fig. 7, pulling upon the block j^3 , carries the center of the toggle past

20 the pivotal points and insures the parts being locked, as above set forth. A set-screw k' , threaded in the stop or rest E', limits the movement of the toggle J J' in the direction which it swings when locking.

25 Two small blocks of leather L or some similar material are let into the stops h^3 of the bracket H in such position that when the switch-track F swings down the ends of the rails of said switching-track will strike these

30 leather blocks and prevent undue noise. For the same purpose a strip of leather L' is placed in the top of the bracket H. This strip prevents any noise due to the striking of the track against the bracket when it flies back

35 to its normal position.

I realize that considerable variations can be made in the details of this construction, and I do not, therefore, desire to limit myself to the specific form herein shown.

40 I claim as new and desire to secure by Letters Patent—

1. In a device of the class described, the combination with a receiving-track, a carrier thereon, and a terminal track above said first track, of a switch-track adapted alternately to form a continuation of that portion of said receiving-track extending toward the cashier's station and said terminal track, substantially as described.

45 2. In a device of the class described, the combination with a receiving-track, a carrier thereon and a terminal track mounted above said receiving-track, of a switch-track adapted alternately to form a continuation of that

50 portion of said receiving-track extending toward the cashier's station and said terminal track, means for bringing said switch-track into the position wherein it is a continuation of said receiving-track and means for bringing said switch-track into the position wherein it is a continuation of said terminal track, substantially as described.

55 3. In a device of the class described, the combination with a receiving-track, a carrier thereon and a terminal track mounted above said receiving-track, of a switch-track adapted alternately to form a continuation of said

receiving-track and said terminal track, of means operated by said carrier when on said receiving-track to swing said switch-track 70 into the position wherein it is a continuation of said receiving-track, and means operated by said carrier when on said switch-track to swing said switch-track into the position wherein it is a continuation of said terminal 75 track, substantially as described.

4. In a device of the class described, the combination with a receiving-track, a carrier thereon, and a terminal track above said receiving-track, of a switch-track above said receiving-track and suitably pivoted to permits opposite ends to be alternately brought into contact with said receiving-track and said terminal track, substantially as described. 85

5. In a device of the class described, the combination with a receiving-track, a carrier thereon, and a terminal track above said receiving-track, of a suitably-pivoted supporting member, a switch-track supported thereby and adapted to be alternately brought into position to deflect carriers from said receiving-track to itself and then to be moved to discharge them upon the terminal track, substantially as described. 90

6. In a device of the class described, the combination with a receiving-track, a carrier moving thereon, and a terminal track above said receiving-track, of a switch-track above said receiving-track and movable with respect thereto, means for bringing one end of said switch-track into position to deflect said carrier from said receiving-track, means for moving said switch-track after said carrier has passed upon it so as to discharge said 105 carrier upon said terminal track, and means for locking said switch-track in said second position, substantially as described.

7. In a device of the class described, the combination with a track, a carrier thereon, 110 and a receiving-track above said first track, of a suitable cam operated by said carrier, a switch-track operated by said cam to deflect said carrier from said receiving-track, and suitable means for moving said switch-track 115 after said carrier has passed upon it to bring its ends into contact with said terminal track, substantially as described.

8. In a device of the class described, the combination with a movable switch, of a bell-crank lever supporting the same, a link connected to the other arm of said bell-crank lever, a second link pivoted upon a center fixed with relation to the pivot of said bell-crank lever, said two links being mutually pivoted 125 together to form a toggle, and means actuated by a cash-carrier to operate said toggle whereby said switch may be moved in one direction and shall be locked in its normal position, substantially as described. 130

9. In a device of the class described, the combination with a suitably-pivoted lever, a cam-surface thereon adapted to be actuated by a cash-carrier, of a second lever connected

to said first lever, a movable switch-track and means of connection between said second lever and said switch-track, substantially as described.

5 10. In a device of the class described, the combination with a receiving-track, of a movable switch-track adapted to be brought into contact with the same, and suitable elastic pads adapted to support the ends of said switch-track when brought into contact with said receiving-track, substantially as described.

11. In a device of the class described, the combination with a receiving-track having a 15 gap in its length, to receive a suitable switch-track, a suitable offset track parallel to said receiving-track and adapted to carry a carrier past said gap, substantially as described.

12. In a device of the class described, the 20 combination with a suitable receiving-track having a gap in its length to receive a suit-

able switch, of suitable yoke-tracks connected to said receiving-track on opposite sides of said gap, and spanning said gap, substantially as described.

25 13. In a device of the class described, the combination with a receiving-track, and a carrier thereon, of a terminal track above said receiving-track, a movable switch-track adapted to deflect a carrier from said receiving-track and a suitable guide-rail above said switch-track adapted to turn said switch-track and deflect said carrier therefrom to said terminal track, substantially as described.

30 35 In witness whereof I have hereunto set my hand, at Chicago, in the county of Cook and State of Illinois, this 21st day of June, A. D. 1902.

WILLIAM L. CHURCHILL.
